UNITED STATES PATENT OFFICE.

HENRY ERNEST PARRY TAYLOR, OF SEYMOUR, CONNECTICUT, ASSIGNOR TO THE COE
BRASS MANUFACTURING COMPANY, A CORPORATION OF CONNECTICUT.

WIRE-DRAWING MACHINE.

974,723.

Specification of Letters Patent.

Patented Nov. 1, 1910.

Application filed June 11, 1908. Serial No. 437,944.

To all whom it may concern:

Be it known that I, HENRY ERNEST PARRY TAYLOR, a citizen of the United States, residing at Seymour, county of New Haven, 5 and State of Connecticut, have invented certain new and useful Improvements in Wire-Drawing Machines, of which the following is a specification.

This invention relates to wire drawing 10 machines and it consists in the novel construction and arrangement of its parts as hereinafter shown and described.

Wire drawing machines as heretofore used 15 have been of relatively complicated construction, which complications have been detrimental to the character of work performed by the machines and have been a source of much expense for installation and maintenance.

20 Among the objectionable features found in such machines may be mentioned, first: complicated lever mechanisms for operating clutch members; second: unsatisfactory means for transmitting movement to the 25 movable parts of the machines, which means lack suitable and simple means for holding the wire reel in position; and third: insufficient provision for the proper adjustment of the parts in order that the wire may be 30 properly presented to the wire block.

The object of this invention is to provide 35 a machine of the character indicated which is of durable construction and simple arrangement of parts and which is adapted to be used for drawing wire of comparatively minute transverse dimensions up to rods of five-eighths of an inch in diameter or thereabout.

40 My machine consists primarily of a rotating shaft from which a wire block is suspended and a simple and durable clutch mechanism for transmitting movement to the said shaft. An effective means is provided for transmitting movement to a worm 45 shaft through which motion is initially transmitted to the movable parts of the machine. A wire reel of special construction is provided. A shiftable plate is mounted upon the bed-plate of the machine and supports the wire reel above mentioned and a die holder in a manner as will be herein- 50 after explained.

The accompanying drawings illustrate my improved invention, in which similar reference characters indicate like parts. 55

Figure 1 is a front elevation of the machine. Fig. 2 is a side elevation of the machine with parts in section. Fig. 3 is a side elevation of a portion of the machine with parts in section showing the clutch members 60 of the machine in engagement with each other. Fig. 4 is a horizontal sectional view of the machine taken on the line 4-4 of Fig. 2. Fig. 5 is a horizontal sectional view taken on the line 5-5 of Fig. 2. Fig. 6 is a 65 horizontal sectional view of a portion of a wire block used upon the machine. Fig. 7 is a vertical sectional view of a wire clamping device mounted upon the said wire block, and Fig. 8 is a vertical sectional view 70 of a shiftable standard mounted upon the machine and carrying a wire reel and a die holder.

The machine is provided with a bed-plate 1, which is mounted upon the base 2. The 75 standard 3 is fixed to the bed-plate 1 and the horizontally disposed shaft 4 is journaled for rotation in the upper portion of the standard 3. The power pulleys 5, 5, are attached to the opposite ends of the shaft 4 80 and the worm 6 is attached to the intermediate portion of the shaft 4 and is housed within the dome 7 located at the upper end of the standard 3.

The provision of a pulley on either end of 85 the shaft 4 is particularly designed to increase the steadiness of operation of the machine. As drive belts running over pulleys will generally exert a partially horizontal pull upon the machine; it will be evident 90 that by securing a drive pulley 5 to each end of shaft 4, swinging movement of the shaft in its bearings which would be caused by horizontal pull on one end of the shaft, will be prevented by horizontal pull in the 95 same direction on the other end. Further, it will be evident that when strain is exerted upon shaft 11, and transmitted through worm wheel 9, to one side of worm 6, said strain will cause swinging movement of 100 shaft 4, and it will be evident that this swinging movement will be prevented by the double pulley arrangement. It will therefore be seen that the double pulley arrange-

ment will equalize or balance the strain upon the machine in transmission of power to overcome the strain upon shaft 11.

The sleeve 8 is journaled for rotation in the upper portion of the standard 3 and the worm wheel 9 is fixed to said sleeve. Said wheel 9 is housed within the casing 10 which communicates with the dome 7 and is also supported at the upper end of the standard 10 3. The wheel 9 meshes with the worm 6. The shaft 11 is journaled in the sleeve 8 and is held therein by the nut 12 screw threaded upon the upper end thereof. The clutch member 13 is fixed to the lower end of 15 the sleeve 8 and is provided with a detachable clutch bit 14. The clutch member 15 is slidably mounted upon the shaft 11 but rotates with the same. The member 15 is provided with a detachable clutch bit 16. 20 The ring 17 surrounds the clutch member 15 and is provided at its sides with the trunnions 18. The yoke 19 pivotally receives the trunnions 18 and is fixed to a shaft 20 which in turn is journaled in the standard 3. 25 The arm 21 is fixed to the shaft 20 and is provided with an adjustable weight 22. The link 23 is pivotally connected at its upper end to the arm 21 and is pivotally connected at its lower end to the lever 24 which in turn 30 is journaled to the side of the standard 3. The wire block 25 is suspended at the lower end of the shaft 11. Said block is substantially conical in configuration and has in its side a recess 26, in which a wire clamping device 27 is pivotally mounted. The said wire clamping device is provided with the movable jaws 28 between which the end of the wire about to be drawn is confined.

The plate 29 is mounted upon the bed-40 plate 1 and has at its opposite sides elongated perforations 30 through which the bolts 31 pass and secure the said plate to the bed-plate. The plate 29 is provided at its outer edge with a depending lug 32 which is 45 provided with a set-screw 33 adapted to operate against the edge of the bed-plate 1 and which is adapted, when turned, to move the plate 29 to or from the wire block 25. The plate 29 is provided upon its upper 50 side with the guides 34 which receive the block 35. The yoke 36 is pivotally mounted upon the block 35 and is adapted to swing horizontally.

The die holder 37 is pivoted in said yoke 55 and is adapted to swing vertically. The block 35 may be adjusted longitudinally in the guides and the die holder 37 has at one end a die receiving socket 38 in which is located a detachable die 39. The die holder 37 is channeled out or troughed throughout its entire length in a plane occupied by the opening in the die 39, so as not to interfere with the feeding of the wire to the said die. The die holder 37 is 60 provided at its end opposite to that to which

the die is applied with a downwardly inclined shank 40 upon which is adjustably mounted a counterbalance weight 41. During the rotation of the wire block the die holder tends to move vertically along the 70 face of the wire block. This tendency varies at different parts of the operation and the adjustable weight is provided to maintain the die-holder in correct position under different strains.

The standard 42 is fixed at its lower end to the guides 34 and is shiftable with the plate 29; consequently, the said standard may move toward and from the wire block 25. The block 35 and its attachments may 80 be shifted laterally with relation to the said wire block. These adjustments are desirable in drawing wire of different diameters. The reel 43 is mounted upon the standard 42 and is adapted to be passed through a 85 coil of wire indicated by the dotted lines 44 in Fig. 1. The said reel is provided at its ends with the plates 45 which are provided at their sides remote from the wire block 25 with the journaled friction rollers 46 90 which also pass transversely through the wire roll and tend to reduce the friction as the wire is unwound from the said roll.

The operation of my machine is as follows: The shaft 4 is rotated by means of 95 belts (not shown) which pass around the pulley wheels 5—5. Inasmuch as the shaft 4 carries the worm 6 which is in mesh with the worm wheel 9 and the power is applied simultaneously to both ends of the shaft 4 100 the tendency of the said shaft to have swinging movement is materially reduced or entirely avoided, thereby reducing to a considerable degree the wear and friction of the shaft in its bearings, and preventing 105 wear and friction upon the worm 6 and worm wheel 9. As the worm wheel 9 is rotated as above described, it carries with it the sleeve 8 and the clutch member 13. When it is desired to rotate the shaft 11 the 110 free end of the lever 24 is depressed, which movement carries down the link 23, which in turn swings the arm 21 and the shaft 20. The yoke 19 is thereby elevated which carries up ring 17 and the clutch member 15 115 so that the said clutch member 15 engages the clutch member 13. As the last said member is rotated the shaft 11 will be correspondingly rotated, which in turn will rotate the wire block 25. The wire 44 has 120 previously been threaded through the opening in the die 39 and secured at its end between the clamping jaws 28 of the pivoted block 27. Therefore, as the said block 27 is carried around with the block 25 the wire is drawn from the reel 43 through the die 39 and is wound upon the wire block 25. At the end of the operation of winding the wire upon the block 25, and when the end of the wire 44 passes through the die 125

39, the convolution of the wire upon the wire block 25 will expand or open up sufficiently to permit the coil of wire to drop from the same after the said block has been 5 brought to a state of rest and the end of the wire is liberated from between the clamping jaws 28.

Thus it will be seen that a machine of simple and durable construction is provided 10 for drawing wire and that the parts are so arranged as to reduce friction and incidental wear and tear to a minimum and the parts may be readily adjusted relatively for drawing wire of different transverse dimensions.

15 Having described my invention, what I claim as new and desire to secure by Letters Patent is:—

1. In a machine of the character described, a rotatable wire block, a die supported upon 20 the machine and a wire reel attached to the machine and adapted to support a coil of wire by passing through the same and having at its side remote from the die, friction rollers which are adapted to pass trans- 25 versely through the coil of wire.

2. A machine comprising a rotatable wire block, a shiftable standard mounted upon the bed of the machine, a die mounted upon 30 said standard and a wire reel mounted upon said standard.

3. A machine of the character indicated, comprising a rotatable wire block, a standard mounted upon the bed-plate of the machine and adapted to be shifted substantially in alinement with the wire block, a die carried by said standard and adapted 35 to be shifted laterally with relation to the wire block and a wire reel carried by the standard.

4. In a machine of the character indicated, 40 a rotatable wire block, a die holder supported upon the bed-plate of the machine and being disposed toward the wire block, a die retained at one end of the die holder, said die holder being channeled out along its 45 entire length in the same plane with the opening in the die and a reel support located above the die holder.

5. In a machine of the character indicated, 50 a rotatable wire block, an adjustable standard mounted upon the bed-plate of the machine, a pivoted yoke mounted for movement with said standard and adapted to swing horizontally, and a die holder pivoted in said yoke and adapted to swing vertically. 55

6. A machine of the character indicated, comprising a rotatable wire block, a standard adjustably mounted upon the bed plate of the machine, a pivoted yoke mounted for movement with said standard and adapted 60 to swing horizontally, a die holder pivoted in said yoke and adapted to swing vertically and a wire reel mounted upon the standard and being located above the die holder.

7. A wire drawing machine comprising 65 wire drawing means, a die holding means, and a reel in superposed relation to said die holding means, said reel being inclined and positioned so that its lower portion is more nearly in a vertical plane with said die holding means than its top. 70

In testimony whereof, I affix my signature, in the presence of two witnesses.
